UNITED STATES PATENT OFFICE.

JOHN BLACK, OF EUREKA, ILLINOIS.

IMPROVEMENT IN HEDGE-TRIMMERS.

Specification forming part of Letters Patent No. 123,224, dated January 30, 1872.

To all whom it may concern:

Be it known that I, JOHN BLACK, of Eureka, in the county of Woodford and in the State of Illinois, have invented a Device for Cutting or Trimming Hedges or Bushes; and do hereby declare that the following is a full, clear, and exact description thereof, reference being had to the annexed drawing making a part of this specification, in which like letters of reference refer to like parts, and in which—

Figure 1 represents the hedge-clamp as used on a hedge; Fig. 2, view of lower surface of same; Fig. 3, end view; Fig. 4, cutter; Fig. 5, end view of same.

This invention consists of two long pieces of timber, (a convenient length being sixteen feet,) jointed together at one end and drawn together by a screw-clamp at the other end, by which means the interior edges of said pieces of timber act as a clamp to draw together into a line the branches of a line of hedge or bushes to be thus held solidly while a saw, if a stout hedge, or a "cutter," if a lighter hedge, is applied to sever the whole edge above the surface of the board or pieces of timber. Scale of drawing is on one-third of an inch to one foot.

A A represents a line of hedge inclosed by the clamp ready for the application of the saw or cutter; B B', two long boards or "scantlings," strengthened by a strip, *a a'*, securely fastened to the inner edge of each board, and also to act as a surface for the saw to move upon. These strips should be covered with a steel plate or bar beveled upward toward the inner edge of the clamp to form an auxiliary cutting-edge, against which the knife or cutter C may operate. The inner edges of each board B B' and strips *a a'* are made slightly convex to obviate any strain (in closing them together) which might tend to make them separate more in the middle than at the ends. The boards are attached together at one end by a joint, *b*, one on either side of the boards, or above and below, being flat bars of iron of equal length, having slots in either end, through which they are bolted to the boards B B', the slots being for the adjustment of the boards at certain distances to suit the size of the branches of the hedge. The remoter ends of the clamp B B' are brought together by a screw-

clamp, *d*, being a screw, *d*, and winch *g* set in a swivel-collar, *e*, beneath the board B' and passing through an eye or staple, *f*, cut with a corresponding thread on the opposite board B. An auxiliary notched catch, *i*, is placed near said screw *d* to hold the ends of the clamp *b b'* together until the end of the screw-clamp can be adjusted in the eye on the opposite board. This catch *i* is simply a pivoted bar notched on one edge, and engaging with a staple on the opposite board. It is designed also to use another screw-clamp at the other end of the hedge-clamp, or even in the middle, if necessary. The cutter C has two curved arms, *h h i i*, both having upright handles at their outer extremities, and are pivoted at their junction or middle part in the clamp *j*, which has a vertical side, *k*, with a sharp edge, (vertical,) *l*, which bites the edge of one of the strips *a a'*, as shown in Figs. 4 and 5, when the cutter is at work. The outer curve of the arm *i i* is a sharp cutting-edge along its whole length.

The operation of this invention is as follows: The jointed pieces B B' are placed horizontally, one at either side of the hedge intended to be cut, the catch *i* and screw *d* being disconnected from the piece B for this purpose. These free ends of the clamp B B' are now pushed together so as to inclose between them all the top branches of the hedge at the height at which it is desired to sever them. The ends bearing the screw-clamp *d* and the notched catch *i* are now temporarily held by the entrance of the latter into its staple until the screw *d* is engaged in the eye *f* of the adjoining piece. The screw is then turned by the winch *g* until all the branches and twigs are reduced to one common line and held solidly between the whole length of the hedge-clamp B B'. (See Fig. 1.) This row of branches may now be severed close to the projecting inner edges of the clamp *a a'* by means of a saw, whose teeth are "filed back" more than the teeth of ordinary cross-cut saws. This saw is used for cutting stout hedges. Smaller or lighter ones are trimmed with the cutter C by placing the vertical side of the pivot-plate *j* (if the operator is on the side of B') against the outer side of the piece "*a*" on clamp B; and at the left end of said board or clamp—one of the handles of the cutter in either hand and the

cutting curved edge pressed against the in-closed branches—the edge of the strip "a" behind said branches, armed with the before-mentioned steel edge, acts as a "shear" in conjunction with the edge of the "cutter" C. The pivot-plate j is prevented from sliding back by the sharp re-entering edge l of the vertical side of said plate j, and, as the branches are severed, the cutter is advanced in this manner, the edge k keeping it up to the branches.

What I claim as my invention is—

1. The hedge-clamp B B' with its raised in-

ner edges a a', joint b, and notched catch i, substantially as described.

2. In combination with raised edges or pieces a a', the cutter C with its pivot-plate j, "side" k, and edge l, and vertical handles l l, substantially as and for the purposes described.

In testimony that I claim the foregoing hedge-clamp and cutter, I have hereunto set my hand this 5th day of October, A. D. 1871.

JOHN BLACK.
